CLAIM

The ornamental design for a fiber cement shingle plank assembly, as shown and described.

DESCRIPTION

FIG. 1 is a perspective view of a fiber cement shingle plank assembly;

FIG. 2 is a front view of the fiber cement shingle plank assembly of FIG. 1 without showing boxed portions;

FIG. 3 is an enlarged view of a first boxed portion of the fiber cement shingle plank assembly shown in FIG. 1;

FIG. 4 is an enlarged view of a second boxed portion of the fiber cement shingle plank assembly shown in FIG. 1; and,

FIG. 5 is an enlarged view of a third boxed portion of the fiber cement shingle plank assembly shown in FIG. 1.
